UNITED STATES PATENT OFFICE.

MARY KAVANAGH, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 15,244, dated August 12, 1884.

Application filed June 23, 1884. Term of patent 3½ years.

To all whom it may concern:

Be it known that I, MARY KAVANAGH, of the city, county, and State of New York, have invented and produced a new and original 5 Design for a Pattern of a Miss's Costume, (numbered 9,308;) and I do hereby declare that the engraved prints accompanying this specification convey to any one accustomed to using paper patterns a clear understanding of how 10 a garment made up by the pattern will appear.

The design shows double-breasted fronts, each of which displays a single box-plait back of the closing edge, and back of the plait descends only a short distance below the hip; a 15 closely-fitted back that displays a single box-plait at each side of the center, and descends

only a little below the waist-line in front of the plaits; a side-plaited skirt depending from the short portions of the back and front at each side; a pocket-lap falling over the top of each side skirt at the center; coat sleeves, and a rolling collar.

What I claim as my invention, and desire to secure by Letters Patent, is—

The design for a miss's costume, as shown in 25 the engraved prints accompanying this specification.

MARY KAVANAGH.
